UNITED STATES PATENT OFFICE.

ALBERT W. J. SCHULER, OF EAST CONCORD, NEW YORK.

DESIGN FOR A PHONOGRAPH-CABINET.

57,195.

Specification for Design.

Patented Mar. 1, 1921.

Application filed July 24, 1920. Serial No. 398,818. Term of patent 14 years.

To all whom it may concern:

Be it known that I, ALBERT W. J. SCHULER, a citizen of the United States, residing at East Concord, in the county of Erie and State of New York, have invented a new, original, and ornamental Design for a Phonograph-Cabinet, of which the following is a specification, reference being had to the accompanying drawing, forming part thereof.

The figure in the drawing is a perspective view of a phonograph cabinet showing my new design.

I claim:

The ornamental design for a phonograph cabinet, as shown.

ALBERT W. J. SCHULER.
